[57] CLAIM

The ornamental design for a bender board holder or similar article, substantially as shown and described.

DESCRIPTION

FIG. 1 is a top plan view of a bender board holder or similar article showing my new design.

FIG. 2 is a front elevational view of FIG. 1.

FIG. 3 is a right side elevational view of FIG. 1, the left side elevational view being a mirror image thereof.

FIG. 4 is a rear elevational view of FIG. 1.

FIG. 5 is a bottom plan view of the bender board holder or similar article.

FIG. 1

FIG. 2

FIG. 3

FIG. 4

FIG. 5
